COMBINED ESCUTCHEON PLATE AND DOORKNOB

Roy Stuart Denker, South Pasadena, Calif., assignor to
Schlage Lock Company, a corporation

Filed Sept. 7, 1962, Ser. No. 71,604

Term of patent 14 years

(Cl. D50—6)

FIG. 3

FIG. 1

FIG. 2

FIG. 4

FIG. 5

FIG. 1 is a front elevation of a combined escutcheon plate and doorknob showing my new design.

FIG. 2 is a side elevation.

FIG. 3 is a partial cross section taken along lines 3—3 of FIG. 1.

FIG. 4 is a sectional view taken along line 4—4 in FIG. 1, showing the knob only in section.

FIG. 5 is a sectional view taken along line 5—5 in FIG. 1, showing the escutcheon plate only in section.

I claim:

The ornamental design for a combined escutcheon plate and doorknob, as shown.
